UNITED STATES PATENT OFFICE.

EPATHA R. H. KREUTNER, OF KANSAS CITY, MISSOURI.

DOLL FURNITURE.

1,290,759.

Specification of Letters Patent.

Patented Jan. 7, 1919.

Application filed June 21, 1916. Serial No. 105,003.

To all whom it may concern:

Be it known that I, EPATHA R. H. KREUTNER, a citizen of the United States, residing at Kansas City, in the county of Jackson and State of Missouri, have invented certain new and useful Improvements in Doll Furniture; and I do hereby declare the following to be a full, clear, and exact description of the invention, such as will enable others skilled in the art to which it appertains to make and use the same.

This invention relates to improvements in furniture, and more particularly to a folding davenport embodying such novel features of construction and simplicity as to especially adapt it for use as a child's toy.

This invention has for its primary object to provide a davenport which may be adjusted for use either as a bed, or lounge.

With this and other objects in view, the invention consists in the novel construction, arrangement and formation of parts as will be hereinafter specifically described, claimed and illustrated in the accompanying drawing, in which:

Figure 1 represents a front elevation of the invention adjusted for use as a couch or lounge,

Fig. 2 represents a plan view thereof, illustrating the invention in extended position for use as a bed,

Fig. 3 represents an end elevation of the invention adjusted as illustrated in Fig. 1,

Fig. 4 represents an enlarged transverse sectional view on the line 4—4 of Fig. 1, showing the flexible bottom supporting frame in dotted lines.

Fig. 5 represents an enlarged vertical sectional view on the line 5—5 of Fig. 2.

Referring to the drawing in detail, where-in similar reference numerals designate corresponding parts throughout the several views, the numeral 6 indicates generally the relatively stationary frame consisting of a pair of spaced longitudinal members 7, connected at their opposite ends by end members 8. The frame 6 is supported upon four legs 9.

A pair of end members 11 are pivotally secured at 12 to angle plates 13 carried by the frame 6 and constitute parts of a relatively adjustable frame, designated generally by the numeral 10, and also including a pair of supporting legs 16 pivotally secured to the end members 11 at 17 and being

connected at their upper ends by a longitudinal member 14. When adjusted in the horizontal position illustrated in Figs. 2 and 5 the relatively adjustable frame 10 is supported upon the legs 16 and the upward swinging movement of the adjustable frame 10 is limited by a pair of abutments 18 adapted to engage the angle plates 13. The legs 16 are connected with the legs 9 by links 19, whereby all of the legs are retained in parallel relation, regardless of the position of the relatively adjustable frame 10.

A fabric bottom 21 is secured along one of its longitudinal edges 22 to one of the longitudinal members 7 of the relatively stationary frame 6 and the remaining edges thereof are secured respectively to the longitudinal and end members 23 and 24, respectively, of a supporting frame for the bottom. The end members 24 of the bottom supporting frame are formed in two sections, the section or part overlying the relatively stationary frame 6 being permanently secured thereto and the other section being hinge- 80 dly secured to the relatively stationary section by hinges 25. The hinged portion of the bottom supporting frame is supported in horizontal position upon a ledge 27 secured to the longitudinal member 14. It will be understood that the bottom 21 is formed of woven wire, or other suitable material having such flexible qualities as to permit the hinged portion of the supporting frame therefor to be moved to the vertical 90 position illustrated in Fig. 1, in which position the hinged portion of the bottom constitutes a back. The axis of the pivots or hinges 25 is removed inwardly, with relation to the relatively stationary frame 6, from the axis of the pivot pins 12, as clearly shown in dotted lines in Fig. 4, so that as the hinged portion of the supporting frame is moved to a vertical position, the longitudinal member 23 is elevated and lies approximately flush with the horizontal member 14 thereby concealing the latter.

What I claim is:

1. In combination, a relatively stationary frame, supporting legs therefor, an adjustable frame pivotally secured to the first mentioned frame, pivoted supporting legs for the adjustable frame, said adjustable frame including a bar rigidly connecting said pivoted legs, means to keep the legs 110

constantly vertical, a flexible bottom, a supporting frame for said bottom including two sections, one of the sections being secured to the relatively stationary frame, means hingedly securing the other section to the first mentioned section and having its axis arranged inwardly of the pivotal connection between the relatively stationary and adjustable frames, and a ledge carried by the said bar and adapted to support the rear portion of said other section in horizontal position when the adjustable frame is extended.

2. In combination, a relatively stationary frame, supporting legs therefor, an adjustable frame including a pair of end mem-

bers, angle plates secured to said stationary frame and pivotally supporting the adjustable frame, a longitudinal member pivotally secured to the free ends of the end members, 20 legs rigidly secured to the longitudinal member, abutments carried by the last-mentioned legs movable against said angle plates, and links pivotally connecting the first and last-mentioned supporting legs. 25

In testimony whereof I affix my signature in presence of two witnesses.

EPATHA R. H. KREUTNER.

Witnesses:
